UNITED STATES PATENT OFFICE.

HENRY M. SORENSEN AND GEORGE W. LEE, OF CHICAGO, ILLINOIS.

SIGN CHARACTER.

1,314,712.

Specification of Letters Patent.

Patented Sept. 2, 1919.

Application filed May 25, 1918. Serial No. 236,457.

To all whom it may concern:

Be it known that we, HENRY M. SORENSEN and GEORGE W. LEE, citizens of the United States, residing at Chicago, in the county of Cook and State of Illinois, have invented certain new and useful Improvements in Sign Characters, of which the following is a specification.

Our invention relates to signs, and has for its object the provision of a simple and efficient sign, and more particularly a character for a sign which can be easily and quickly repaired, and one which may be economically manufactured and durable in use. Other objects will appear hereinafter.

An embodiment of our invention is shown in the accompanying drawing, forming a part of this specification, and in which—

Figure 1 is a side view of a portion of a sign embodying our invention.

Fig. 2 is a section taken on line 2—2 of Fig. 1.

Fig. 3 is an enlarged fragmental detail taken on line 3—3 of Fig. 1.

Figs. 4 and 5 are views similar to Fig. 3 showing modified forms of parts of the construction; and

Fig. 6 is an enlarged fragment showing a corner portion of a character used in the construction.

Referring more particularly to the drawing, we have shown a sign suitable for illuminating the characters thereof, and in the form shown a box made up of a rear wall 7, front wall 8, and edge walls 9 are formed of any suitable material, such as sheet metal. The walls may be put together in any desirable manner. Inside of the walls a suitable number of lamps 10 may be provided for illuminating the characters of the sign. The lamps 10 may be electric lamps, as indicated, or any other desirable illumination means may be supplied.

This invention is directed more particularly to the characters making up the sign referred to. In these characters any desirable substance may be used to represent the characters. We find that glass plate or celluloid plates serve admirably for forming the main parts of the characters. These glass or celluloid plates may be formed in any desired colors, or formed transparent when so desired, so that during the day time the sign will be attractive, and after dark the lamps 10 will illuminate the

sign to render it useful at these times as well.

The plates of glass or celluloid may be formed in any particular or convenient sizes, and are preferably made in such sizes and shapes that they will fit together easily and quickly, and so that the signs can be made up at the places where they are to be put into use by persons of no great skill. In the drawing we have indicated one letter, but it will be apparent that any letter or character can be made up in the same manner that this letter is formed.

In the sign shown the front wall 8 has openings cut therein representing the desired characters which are to be shown on the sign. In each of the character openings a plurality of plates 11 are provided, which when fitted together substantially fill said opening. The sheets 11 are preferably fitted together so that they can easily be made from strips of material by cutting to the desired shapes. Around each of the sheets 11 we provide an independent frame 80 which is preferably made up of a single strip of long narrow thin material. We find zinc, or other soft metals quite suitable for this purpose, although celluloid and many other materials may answer as well. 85 The material making up the frame 12 is preferably made in long strips having a cross-section, substantially as indicated in Figs. 3 and 4, and when it is desired to make up a sign the long strips of material are 90 cut and bent around the sheets of material 11 to form frames. Each of the frames 12 has the strip of which it is formed laid around closely on a sheet 11 with the ends 95 thereof brought together preferably on a plane side of a sheet 11 and secured together by means of solder, or the like. The strip of which each frame 12 is formed has an intermediate portion 14 which runs throughout its length disposed around the 100 edges of a sheet 11. This part 14 is not severed at the corners of the sheet 11 and is the part which holds the sides of the frame together. At each side of the intermediate portion 14 is a portion 15 which is disposed on opposite sides of the sheet 11 adjacent the edge of the latter. At the corners the parts 15 are notched and fitted together as at 16 so that such parts 15 will lie flatly against the sides of the sheet 11, including 110 the corners of the latter. One of the parts 15 has a part 17 which is bent back against

such part 15 and extends beyond the latter providing a flange adapted to be secured to the plate 8 for holding the character in place. In Figs. 1, 2 and 3 this flange 17 is disposed on the inner side of the plate or side 8, and in Fig. 4 this flange 17 is secured to the outer side of plate 8. The flange 17 may be secured to the plate 8 by the use of solder, or any other desirable means.

10 In Fig. 5 we have shown a slightly modified form of the frame 12 which consists in providing a portion 18 between the flange 17 and its part 15. This part 18 provides means for raising the character away from the plate 8 so as to indicate raised letters or characters. It will be apparent that while the part 18 is disposed substantially in the same plane as the part 14 in Fig. 5, that this part 18 may not always lie in this same plane, but may be disposed at an angle to the plane of part 14. The long strip from which the frames are cut may be formed on dies (not shown), or in any desirable manner, and set up and fitted to the plates 11 as the character is formed, and be done either in a shop or out where the sign is to be erected.

While we have illustrated and described the preferred form of our invention, we do not desire to limit ourselves to the precise details set forth, but desire to avail ourselves of such variations and changes as come within the scope of the appended claims.

35 We claim:—

1. A character for signs comprising a plurality of separate sheets of material arranged to represent a character; a frame around each of said sheets made up of a single piece of sheet material having an intermediate portion throughout its length disposed against the edges of said sheet and edge portions adjacent said intermediate portion disposed on the sides of said sheet; and means securing said frames together.

40 2. A character for signs comprising a plurality of firm sheets arranged to represent a character, a frame around each of said firm sheets made up of a single piece of thin

sheet material having an intermediate portion throughout its length disposed against the edges of said sheet and portions adjacent said intermediate portion disposed on the sides of said sheet holding the latter in position, and one longitudinal edge of said frame material forming a supporting means for said frame and firm sheet; and means securing said frames together.

3. A character for signs comprising a plurality of transparent sheets arranged to represent a character; and a frame around each transparent sheet made up of a single piece of thin sheet material having an intermediate portion throughout its length disposed against the edges of one of the transparent sheets and edge portions adjacent said intermediate portion disposed on the sides of said transparent sheet, said edge portions being notched at the corners of said transparent sheet for fitting the sections of the edge portions together without overlapping each other on said transparent member.

4. A character for signs comprising a plurality of transparent sheets arranged to represent a character; a frame around each transparent sheet made up of a single piece of thin sheet material having an intermediate portion throughout its length disposed against the edges of one of the transparent sheets and edge portions adjacent said intermediate portion disposed on the sides of said transparent sheet, said edge portions being notched at the corners of said transparent sheet for fitting the sections of the edge portions together without overlapping each other on said transparent member, and one longitudinal edge portion of each strip being disposed substantially parallel with one side of the transparent sheet providing a supporting flange for the frame and transparent sheet; and means securing the adjacent sides of the frames together.

In testimony whereof we have signed our names to this specification on this 18th day of May, A. D. 1918.

HENRY M. SORENSEN.
GEORGE W. LEE.
